UNITED STATES PATENT OFFICE

2,646,629

FORCED AIR DRIER

George S. Clemens, Evanston, Ill., assignor to
 National Dryer Manufacturing Corporation,
 Chicago, Ill., a corporation of Illinois

Application September 26, 1952, Serial No. 311,689

5 Claims. (Cl. 34—243)

1

This invention relates to a forced air dryer, and is particularly useful for the drying of the hands. Other uses will be obvious.

In hand dryers employed in washrooms at plants, public buildings, etc., it is of the utmost importance that the dryer be a safe instrument and be protected against injury and that the air delivered from the dryer be heated to a maximum degree consistent with safe operation.

An object of the present invention is to provide the above desired results while furnishing an efficient stream of uniformly-heated air for quick drying of the hands. A further object is to provide such a structure which is protected against injury by careless or wanton persons while at the same time protecting such persons against harm and while also providing a stream of highly and uniformly heated air. Other specific objects and advantages will appear as the specification proceeds.

The invention is shown, in an illustrative embodiment, by the accompanying drawing, in which—

Figure 1 is a vertical sectional view of a forced air dryer embodying my invention; and Fig. 2, a detail view, the view being taken, as indicated, at line 2—2 of Fig. 1.

In the illustration given, 10 designates a housing having a flat back portion adapted to be received on a vertical surface, such as a wall. The housing has a relatively flat front panel 11 extending downwardly and rearwardly. An air-directing nozzle 12 projects from the flat panel 11.

In the illustration given, the panel 11 slopes at about 20 degrees relative to the flat back portion of the housing. It is provided with a circular opening 13 which receives the bushing or ring 14. The bushing or louver ring is held in position by the annular member 15 which is threadably received on the surface of the bushing within the housing 10. The member 15 provides an overhanging annular surface in which the rubber or resilient washer 16 is received. The ring 14 is provided with an outwardly-extending flange 17 which bears against a sealing gasket 18.

A fan scroll 19 is mounted within the housing 10 and has its outlet opening in registry with the air discharge opening 13 in panel 11. An impeller (not shown) is carried by the shaft 20, which in turn is driven by a motor (not shown) during operation. Rotation of the impeller causes air to travel from scroll 19 outwardly through the louver ring or bushing 14 and through the curved nozzle 12.

The air-directing nozzle 12 is adapted to de-

10 flect air at an angle of substantially 70 degrees relative to the panel 11. This nozzle has an annular recess receiving the bushing or louver ring 14 and a snap ring 21 is received in cooperating annular grooves in bushing 14 and nozzle 12. If it is desired to prevent rotation of the nozzle 12 and lock it in a downwardly-facing direction, I provide a setscrew 22 for the purpose, as indicated in Fig. 1. It will be understood that any suitable means for locking the nozzle 12 in a downwardly-facing direction may be employed.

15 The scroll 19 receives the heating unit 23, as shown more clearly in Fig. 1. This unit, consisting of heat resistance elements, is received in the outlet duct portion of scroll 19 and heats the air discharging from the scroll. A detailed description of the heating unit, and associated parts, is set out more fully in my co-pending application, Serial No. 79,051, filed March 1, 1949, now Patent No. 2,634,514.

20 The louver ring or support 14 is provided in its upper portion with a number of louvers 24 which are parallel and which extend forwardly in a straight line. Such louvers extend substantially at right angles to the panel 11. Below louvers 24 and in the lower portion of the support 14, are a series of louvers which are tilted forwardly and inwardly. The lowermost louver 25 has its inner end merging with the support 14 and its forward end portion tilted forwardly and upwardly. The next louver 26 there-above is also tilted forwardly and inwardly. Louver 27 has also an inclination similar to that of 25 or 26, but to a lesser degree. Louver 28 inclines forwardly and inwardly, but at a less angle of inclination than that of louver 27. The louvers 24, being straight and parallel, direct the heated air forwardly in straight paths toward the wall of the downwardly-curved nozzle 12. The lower louvers 25 to 28, inclusive, direct air at an angle to the streams projected by the louvers 24 and, if the streams on the several louvers were projected far enough without obstruction, such streams would intercept. With the structure shown, the louvers cooperate with the downwardly-turned nozzle in bringing the several streams into contact, producing a turbulence which is highly effective in bringing about a uniform air admixture which strikes the hands for rapid drying. At the same time, the structure shown prevents anyone from extending a straight instrument or device through the nozzle opening and into contact with the electric resistance elements 23. It will be observed that the sharply-inclined louvers 25, 26, 27 and 28 which are nearest the mouth of the nozzle present a uni-

form barrier to the entrance of any such instrument, while the remote position of the louvers 24 similarly prevents the extension of any rod or straight device into the interior of the scroll 19.

With the foregoing structure, the louver arrangement not only is effective in bringing about a turbulent and uniform mixture of the air streams, but also prevents injury to the electric resistance elements or to the persons tampering therewith by reason of the relative angular positioning of the louvers. 10

In the operation of the structure, the user stands adjacent the dryer with his hands below the nozzle 12 and closes a switch to complete circuits in which the blower and resistance elements lie. Air is forced through the outlet of the scroll 19 past the heater elements 23 and thence through the louvers 24, 25, 26, 27 and 28 and thence downwardly through the nozzle 12 onto the hands of the user. Drops of water upon 20 the hands are directed downwardly and away from the clothing of the user, while at the same time the highly heated turbulent air is maintained at a uniform temperature throughout which is effective in producing a quick drying of the hands.

If desired, the setscrew 22 may be partially withdrawn so as to make the nozzle 12 rotatable. I prefer, however, for the purposes of the invention herein, to lock the nozzle 12 against rotation 30 so that the nozzle is permanently maintained in the downwardly-facing direction shown.

While, in the specific illustration given, I have set forth a single structure in considerable detail for the purpose of illustrating an embodiment of the invention, it will be understood that such details of structure may be varied widely by those skilled in the art without departing from the spirit of my invention.

I claim:

1. In a forced air dryer, a casing equipped with a downwardly-curved discharge nozzle, an electric resistance element in said casing adjacent said nozzle, means for energizing said element, means for discharging air past said resistance element and through said nozzle, a louver support mounted in the discharge portion of the casing and louvers carried by said support, the louvers in the upper portion of the support being substantially straight and parallel and the louvers in the lower portion of the support being inclined forwardly and upwardly. 50

2. In a forced air dryer, a casing equipped with a downwardly-turned discharge nozzle having a substantially horizontal discharge mouth, an electric resistance element in said casing adjacent said nozzle, means for energizing said element, means for discharging air past said resistance element and through said nozzle, a louver ring

mounted in the discharge portion of the casing adjacent said nozzle, and a plurality of louvers extending across said ring, the louvers in the upper portion of said ring extending in a generally horizontal parallel arrangement and the louvers in the lower portion of the ring being tilted forwardly and upwardly, whereby said louvers provide a barrier to any straight instrument extending through the mouth of said nozzle. 5

3. In a forced air dryer, a casing providing a blower and heater chamber and having a downwardly-curved nozzle extending therefrom for the discharge of heated air, means within said casing for heating and delivering air through said nozzle, and a louver ring mounted in said casing adjacent said nozzle and having transverse louvers mounted therein, the upper portion of said louvers being substantially horizontal and parallel for directing air in streams forwardly against the curved wall of the nozzle and the lower portion of said louvers being inclined forwardly and inwardly, whereby intersecting air streams within the nozzle produce a turbulence of the discharged air. 15

4. In a forced air dryer, a casing providing a heating and blower chamber and a downwardly-curved discharge nozzle leading therefrom, means for heating air and forcing the same through said nozzle, and a louver support mounted in the inlet portion of said nozzle and having louvers extending transversely thereof, the upper portion of said louvers being substantially horizontal and parallel and the lower portion of said louvers being inclined upwardly and inwardly, the lowermost of said louvers being its rear portion merging with said support throughout the width of the louver. 20

5. In a forced air dryer, a casing providing a heating and blower chamber and a downwardly-curved discharge nozzle leading therefrom, means for heating air and forcing the same through said nozzle, and a louver support mounted in the inlet portion of said nozzle and having louvers extending transversely thereof, the upper portion of said louvers being substantially horizontal and parallel and the lower portion of said louvers being inclined upwardly and inwardly, the latter louvers being inclined forwardly and inwardly the nearer they lie to the center of the support. 35

GEORGE S. CLEMENS.
